UNITED STATES PATENT OFFICE.

EUGENE PEARL, OF NEW YORK, N. Y.

CHAIR PAD.

Application filed March 14, 1921. Serial No. 452,191.

To all whom it may concern:

Be it known that I, EUGENE PEARL, a citizen of the United States, and a resident of New York city, in the county of New York and State of New York, have invented certain new and useful Improvements in Chair Pads, of which the following is a specification.

This invention relates to improvements in seat coverings or chair pads and has as its principal object the provision of means for yieldably confining the pad upon the seat, but permitting it to move in any direction, as to the front or side over the surface of the seat, returning it to normal position when released.

A further object is to provide such confining means almost wholly embedded within the fabric of the pad or cushion, thus being invisible and nonperceptible to the user, and which permits the pad to be raised from the seat for cleansing and like purposes.

Another object is to produce an efficient attaching means secured to a portion of the seat not accessible to the users or their clothing.

A still further purpose is to provide a fastening means which will permit the pad to be reversed, thereby presenting a fresh surface, which may be of a different color.

These and other like objects, which will become manifest as the description progresses, are attained by the novel construction, combination and arrangement of parts hereinafter described and shown in the accompanying drawings, forming an essential part of this disclosure, and in which:—

Figure 1 is a fragmentary perspective view of a conventional type of chair, showing the application of the pad.

Figure 2 is a plan view of the seat, the upper element of the chair being in section, showing in full lines the normal disposition of the pad and indicating in broken lines the various positions it may assume when in use.

Figure 3 is an enlarged fragmentary plan view of the pad and attaching means.

Figure 4 is a sectional view taken on line 4—4 of Figure 3.

Stated in general terms the invention, which is characteristically simple in its nature, comprises any preferred type of pad, cushion or like seat covering, the same containing apertures in its rear edges in which are confined elastic elements, secured at their extending ends to the chair body.

Referring to the drawings in detail, the numeral 10 designates the seat of a common chair, provided with legs 11, arms 12 and back elements 13.

A pad or analogous element 15, usually made of felt and used to prevent the shiny appearance of clothing, due to continuous sliding contact with the hard polished surfaces of common chairs, is split or apertured at preferably two points in its rear edge as at 16, and has inserted in the openings thus made, elastic or tensional members, as the close helical spring 17 indicated.

The terminal coils of the spring are bent outwardly in a horizontal plane, preferably two adjacent convolutions 18 at each end and have passed through them eyelets or tubular rivets 19, which are then upset enclosing the coils 18 rigidly between the ends of the rivets.

One of these riveted ends is secured at the bottom of each opening by stitching 20 in a secure and positive manner, while the other extending end has passed through the opening in the rivet a common wood screw 21, held from displacement with the spring end by a washer 22 forced over the body of the screw from its point end as shown. It is to be understood that any form of tension element, as a flattened coil or zig-zag wire spring, rubber tape or equivalent elastic material may be used and that the fastening devices may be of any approved type.

In operation the pad, cushion or other article is placed in proper position on the chair seat, and the screws 21 inserted in the usual manner, nothing being exposed except the head of the screw and pad itself.

The garments coming in contact with the pad tend to slightly adhere, causing the pad to move with the body of the person using the chair over the surface of the seat, as is well known; upon rising from the seat the elastic elements instantly restore the pad to its initial position and, due to the hinge effect of the fastenings, the pad can at any time be raised for cleaning or other purposes, and also reversed if a single fastening element is used by merely raising and turning the pad.

While in the foregoing there has been shown and described the preferred embodiment of this invention, it is to be understood that certain minor changes, in the details of construction, combination and arrangement of parts may be resorted to with-

out departing from the spirit and scope of the invention as claimed.

I claim—

In a device of the class described, the combination with a seat, of a pad disposed over the seat, coiled springs disposed in apertures formed in the rear edge of said pad, said springs having their end coils bent outwardly forming eyes, eyelets fixed in the

eyes, means for attaching the eyelet at the 10 inner end of said spring within the fabric of the pad, and means for attaching the eyelet at the outer end of said coil to the seat.

In testimony whereof I have signed my 15 name to this specification.

EUGENE PEARL.
